UNITED STATES PATENT OFFICE

FLOYD L. SCOTT, OF HOUSTON, TEXAS, ASSIGNOR TO HUGHES TOOL COMPANY, OF
HOUSTON, TEXAS, A CORPORATION OF TEXAS

DRILL CUTTER RETAINING RING

Application filed May 4, 1929. Serial No. 360,371.

My invention relates to means for retaining a drill cutter rotatably upon its bearing. It is particularly adapted for use with conical shaped cutters, such as are now used in drilling rock or other hard formation in well drilling operations.

The cutters upon which the invention is employed are mounted upon a bushing or bearing which has to be threaded or otherwise engaged upon the end of a supporting pin or shaft. The bushing is frusto-conical in shape and the cutter is mounted on the bushing to surround the end of the bushing and the shaft. The cutter is retained in position rotatably upon the bushing by a retaining ring screwed into the base of the cutter behind the large diameter of the bushing.

Difficulty has been experienced in operating cutters thus mounted because of the great strains to which the device is subjected in use, tending to force the cutter off the end of the bushing and tearing the retaining ring from its seat. Further, it is necessary in screwing the assembled cutter and bushing upon the shaft that the cutter and bushing be held non-rotatably together while the bushing is screwed upon the shaft. An opening is provided in the side of the cutter extending into the bushing so that a pin may be introduced into the said bushing to rotate it about the shaft in screwing it thereon. This opening must be comparatively large to receive a pin strong enough to unscrew the cutter and bushing after it has become fixed in the shaft in operation. The opening cannot be large if it is to extend through the ring or the ring will be unduly weakened.

My invention has for its object, the provision of a cutter of the type described in which the retaining ring may be formed of sufficient length to be firmly attached to its seat in the cutter and is not greatly weakened by the wrench pin opening.

I desire to form a large wrench pin opening along the large diameter of the cutter and still not materially weaken the ring by means of which the cutter is held upon the bushing.

In the drawings herewith, Fig. 1 is a central longitudinal section through a drill cutter showing my improved means for locking the cutter upon its bushing.

Fig. 2 shows a side and end elevation of the retaining ring.

In illustrating my invention, I have shown a cutter having a body 1 of frusto-conical shape having its base beveled somewhat at 2 to form a gauge surface. The cutter has circumferential rows of teeth 3 thereon of ordinary construction.

The cutter has an interior frusto-conical shaped socket 4 therein to fit about a bushing 5. Said bushing has a reduced neck 6 connecting with its base, said neck terminating approximately flush with the base of the cutter. A shoulder 7 is thus formed on said bushing to bear against a retaining ring 8 which secures the cutter on said bushing.

The cutter socket 4 has a threaded seat 9 into which the retaining ring may be screwed and an annular recess is formed at the outer end of said seat to receive a bond of welding material 10 by means of which the ring is rigidly held in position.

The ring 8 is formed of sufficient length to make a strong attachment with the cutter. It has at one point, along its inner end, a semicircular notch 11, formed to allow the passage of a wrench pin of the usual construction.

The wrench pin is used to rotate the bushing to screw it upon its shaft when the cutter has been assembled thereon and locked in position. An opening 12 is formed radially through the wall of the cutter and this opening is threaded at 13 to receive a stop plug when the wrench is not in use. The bushing has a recess 14 to receive the end of the wrench pin.

In forming the notch in the ring, it is first screwed firmly into its seat and a tool is inserted through the opening 12 in the cutter and a mark is made upon the ring by said tool to show where the notch should be. The ring is then unscrewed and the notch is formed and the ring again screwed in place. The notch is not deep enough in the ring to materially weaken it and the

opening 12 may be large enough to receive a pin large and strong enough to unscrew the cutter and bushing from the pin without danger of breaking the wrench. It is to be understood that the rotation of the well drill in the well tends to screw the bushings so tightly upon the cutter shafts as to practically "freeze" the bushing on the shaft and great force must be exerted upon the bushing in unscrewing it from the said shaft.

The opening 12 is closed by a threaded plug of the usual construction, not shown, extending short of the bushing 5 to prevent mud and slush from entering the bearing, but allowing rotation of the cutter on the bushing.

The construction thus described differs from prior similar constructions in that provision is thus made for a long retaining ring, which cannot be forced from its locking position to allow the cutter to be lost in use. Also, the locking ring is not materially weakened even though a large wrench pin opening is formed in the cutter and bushing.

What I claim as new is:

1. In a drill cutter, a frusto-conical bushing threaded internally to screw upon the end of a shaft, a reduced neck on said bushing, a cutter fitting over and enclosing one end of said bushing, a retaining ring shaped to fit about the neck of said bushing, and screw into a threaded seat in said cutter, there being an arcuate notch on the inner end of said ring to allow passage of a wrench pin to engage within a registering opening in said cutter and into a recess in said bushing.

2. In a drill cutter, a frusto-conical bushing threaded internally to screw upon the end of a shaft, a reduced neck on said bushing, a cutter fitting over and enclosing one end of said bushing, a retaining ring shaped to fit about the neck of said bushing, and screw into a threaded seat in said cutter, there being an arcuate notch on the inner end of said ring to allow passage of a wrench pin to engage within a registering opening in said cutter and into a recess in said bushing, and means to hold said retaining ring rigidly in position.

3. In a drill cutter a bushing, a shoulder on said bushing, a frusto-conical shaped cutter enclosing one end of said bushing, means to retain said cutter on said bushing including a ring screwed within said cutter and engaging a shoulder on said bushing, said cutter and bushing having registering opening therein to receive a wrench pin, and a notch formed in said ring to register with said wrench pin openings.

In testimony whereof I hereunto affix my signature, this 16th day of April, A. D. 1929.
